UNITED STATES PATENT OFFICE.

ERNEST K. VAN BUSKIRK, OF BINGHAMTON, NEW YORK, ASSIGNOR OF ONE-HALF TO
HAROLD IVAN HARRIS, OF BINGHAMTON, NEW YORK.

WORK HOLDER FOR ENDLESS CONVEYERS.

1,418,185.

Specification of Letters Patent. Patented May 30, 1922.

Application filed April 19, 1920. Serial No. 375,099.

To all whom it may concern:

Be it known that I, ERNEST K. VAN BUSKIRK, a citizen of the United States, residing at Binghamton, in the county of Broome 5 and State of New York, have invented certain new and useful Improvements in Work Holders for Endless Conveyers; and I do declare the following to be a full, clear, and exact description of the invention, such as 10 will enable others skilled in the art to which it appertains to make and use the same.

The invention relates to work holders, and more specifically to an improved work holder for an endless conveyer, chain-conveyer 15 or other flexible conveyer of this character.

The main object of this invention is to provide an improved conveyer-lug or chuck having an inclined work-seat and a work-engaging element or retaining jaw having a 20 work-engaging seat or surface parallel with said work-seat, so that a bar having parallel surfaces can be snugly fitted between this seat and the retaining jaw and held thereby while being conveyed horizontally into engagement with a machine-tool to operate on a corner of this bar.

A further object is to provide an improved and simple means whereby this chuck can be angularly adjusted so as to 30 change the degree of inclination of the work-seat and retainer.

A further object is to provide a work-holder or chuck of this character which is adjustable for conforming to work of different dimensions.

Other objects and advantages will be pointed out or implied in the following details of description, in connection with the accompanying drawings in which:—

40 Fig. 1 is a side elevation of a portion of a conveyer and certain associated parts of a tenoning machine, this conveyer being provided with my improved work-holding device, the work being illustrated in dotted lines.

Fig. 2 is a top plan view of the conveyer illustrated in Fig. 1, a portion of the conveyer shaft being broken out.

Fig. 3 is an enlarged front end elevation 50 of my improved work-holding device.

Fig. 4 is a sectional view, the section being taken along the line 4—4 of Fig. 3.

Fig. 5 is a horizontal sectional view, the section being taken along the line 5—5 of Fig. 4.

Fig. 6 is a vertical sectional view along the line 6—6 of Fig. 4.

Fig. 7 is a perspective view showing the sliding or telescopic connection of the jaws with the base or base-plate.

Fig. 8 is a vertical sectional view of a modified form of the invention, the section being taken substantially along the line 8—8 of Fig. 9.

Fig. 9 is a vertical sectional view, the section being taken substantially along the line 9—9 of Fig. 8.

Fig. 10 is a perspective view illustrating the two main elements of this modified form separated from one another.

Referring to these drawings in detail, in which similar reference characters correspond with similar parts throughout the several parts, and in which the sprockets or driving wheels 1, driving shaft 2, guide-beam 75 3, and holding-down device 4 are of ordinary construction, the invention consists in the construction and arrangement of parts which will now be described as follows:

According to the form illustrated in Figs. 1 to 7, inclusive, the device comprises a link 5, a base-plate 6, a lower jaw or work-piece 7, an upper jaw or work-holding element 8 and other minor elements such as screws 9 and 10.

The base-plate 6 is provided with a laterally extending rib or ridge whose lateral edges constitute shoulders or abutments 11, and the link 5 is provided with a corresponding pair of shoulders between which the shoulders 11 are seated, and against which they are fitted. The base-plate 6 is provided with an aperture therethrough, indicated at 12 in Fig. 7, and the screw 9 extends therethrough into engagement with the link 5.

It will be seen, therefore, that each shoulder 11 cooperates with the screw 9 for securing the base-plate 6 on the outer surface of the link 5.

A hollow stud or socket 13 extends out-

ward from the outer major surface of the base-plate 6, and the jaw 8 is provided with a shank 14 which is slidably fitted in the socket 13. The shank 14 and hollow of the 5 socket 13 are preferably of dove-tail construction, in cross section, as shown in Fig. 5, and the screw 10 can be loosened to permit the jaw 8 to be moved toward and from the base-plate, and can be tightened for 10 securing the jaw 8 in its different adjustments. The work-engaging surface of the jaw 8 and the work-carrying surface of the jaw 7 are substantially parallel with one another, and are inclined or oblique to the inner and outer 15 major surfaces of the base-plate.

The base-plate 6 is provided with a groove 15 which extends longitudinally or in the direction of travel of this plate, and the jaw 7 is provided with a corresponding 20 tongue 16, this tongue and groove being preferably of dove-tail construction, as shown, and the tongue 16 is slidable longitudinally in the groove 15 to provide adjustment toward and from the jaw 8. A screw 17 is 25 provided to bear against the tongue 16 and hold the jaw 7 in its different adjustments. It will be seen, therefore, that a bar having parallel opposite sides, as indicated at W in Fig. 4, can be snugly fitted between the work-engaging surfaces of the jaws 7 and 8, and held by these jaws in a laterally inclined 30 position so that a saw or dado-head of a wood-working machine (for instance) can cut a kerf or dado at a predetermined angle 35 to the major sides of the bar or work W. It is to be understood, of course, that two of the devices are employed, that is, two of the work-holders such as shown in Fig. 4, one on each of two parallel chains, as shown in 40 Fig. 2. By adjusting the jaws 7 and 8, or one of them, bars or pieces of work of various thicknesses can be placed therebetween.

In the form illustrated in Figs. 8, 9 and 45 10, the link 5 and its connection with the base-plate is substantially the same as that previously described, that is, the base-plate is provided with shoulders 11, and an aperture 12 which receives the securing screws 9. However, the upper major surface of 50 this base-plate 6^a is arcuate or concaved, and its dove-tail groove 15^a extends from front to rear, throughout its entire length, and is arcuate in conformance with the degree 55 of curvature of its adjuncts. The upper edges of this groove are disposed in parallel planes which are at right angles to the major sides of the base plate 6^a, and the dove-tail rib 16^a is formed on a work-engaging member which is formed of a single piece and includes upper and lower jaws 7^a and 8^a. These jaws are of the same general construction 60 and for the same purpose as the jaws 7 and 8 previously described, and their work-engaging surfaces are oblique to the inner 65 major surface which is seated upon the link

5. However, these jaws 7^a and 8^a, instead of being adjustable with relation to one another, are mutually adjustable with relation to the base-plate 6^a; that is, the tongue 16^a is slidable along the groove 15^a, and obviously, by thus adjusting these members with relation to one another, the angularity of this pair of jaws or this bifurcated member 7^a—8^a is changed with relation to the major surfaces of the base-plate. A screw 75 17, similar to that previously mentioned, abuts against the rib 16^a for securing it in its different adjustments along the groove 15^a.

Although I have described these embodiments of my invention very specifically, it 80 is not intended to limit this invention to these exact details of construction and arrangement, but changes may be made within the scope of the inventive ideas as implied and claimed.

What I claim as my invention is:

1. In a work-holding device for a chain conveyer, a chain-link, a base-plate seated on and united with the outer side of said chain-link, a jaw mounted upon said base-plate and adjustable longitudinally of the same, means for releasably holding said jaw in an adjusted position, and a second jaw extending in overhanging relation to the first jaw and having a work-engaging face 95 extended parallel to the work-engaging face of the first jaw.

2. In a work-holding device for a chain-conveyer, a base-plate attachable to the outer side of a chain link, a jaw mounted on the 100 outer side of said base-plate and being adjustable longitudinally of the latter, means to hold said jaw in its different adjustments, and a second jaw adjustably mounted on said base-plate for adjustment toward and 105 away from the first mentioned jaw and having a work-engaging surface extending parallel to the work-engaging surface of the first jaw and cooperative with the first mentioned jaw to hold a bar therebetween.

3. In a work-holding device for a chain-conveyer, a chain-link, a base-plate seated on and secured to the outer side of said link, said base-plate having a groove in and extending along its outer surface, a work-seat 115 disposed obliquely to the outer surface of the base plate and provided with securing means including an element extending into and adjustable along said groove, and a work-engaging jaw cooperative with said 120 work-seat to hold a bar or other work in an oblique position.

4. The structure defined by claim 3 having the base plate provided with a socket, the jaw slidably fitting into the socket for 125 movement toward and away from said groove, and means for securing the jaw in an adjusted position.

5. In a work-holding device for a chain-conveyer, a chain-link, a base-plate united 130

with said chain-link and provided at one end with a work-seat which is oblique to the outer side of the link, said base plate having a socket at its opposite end, a jaw having 5 a shank seated in said socket and movable therein towards and from said work-seat, and means to hold said shank in its different adjustments, said jaw having a work-engag-

ing surface which is oblique to said outer side of the link and is cooperative with said work-seat to hold work therebetween in a laterally inclined position.

In testimony whereof I have hereunto set my hand.

ERNEST K. VAN BUSKIRK.
